UNITED STATES PATENT OFFICE.

NATHAN H. BERGSTROM, OF NEENAH, WISCONSIN.

CYLINDER FOR PAPER-PULP MACHINES.

Application filed July 21, 1924. Serial No. 727,237.

This invention relates to improvements in paper pulp cleaning machines, and more particularly to a cylinder for the same.

In the manufacture of paper, either from rags or from wood pulp, it is customary to first subject the pulp to the action of water to remove foreign matter from the pulp before it is treated with chemicals. For this purpose, a plurality of connected together compartments are used and a drum is revolved in each compartment. The drums are covered with wire meshing and the pulp in each compartment is subjected to jets of water to cleanse the same. Each drum is eccentrically mounted within its compartment and as it revolves it squeezes the pulp against the compartment wall to free the same from the dirty water, and the pulp is carried to the next compartment. The dirty water passes through the wire meshing of the drum and is directed from the compartment.

It is, therefore, one of the objects of the present invention to provide a cylinder of the class mentioned, constructed to permit the ready replacement of the wire meshing or screens.

A further object of the invention is to provide a cylinder of the class described in which the grates, provided to support and protect the screens, are removable from the drum with, or independently, of the screens.

A further object of the invention is to provide a cylinder for paper pulp machines of sectional construction to permit the easy removal of any of the parts for repairs or replacement.

A further object of the invention is to provide a cylinder for paper pulp machines which is of very simple construction, is efficient in operation, is strong and durable, and is well adapted for the purpose described.

With the above and other objects in view, the invention consists of the improved cylinder for paper pulp machines and its parts and combinations as set forth in the claims, and all equivalents thereof.

In the accompanying drawing, in which the same reference characters indicate the same parts in all of the views:

Fig. 1 is a side view of the improved cylinder for paper pulp machines, part being broken away and shown in section;

Fig. 2 is an end view of the cylinder, part being broken away and shown in section;

Fig. 3 is an enlarged fragmentary detail view to show the head joint construction;

Fig. 4 is a sectional view taken on line 4-4 of Fig. 3;

Fig. 5 is a sectional view taken on line 5-5 of Fig. 3;

Fig. 6 is a fragmentary view of the inner face of one of the drum heads;

Fig. 7 is a cross-sectional view of a drum head;

Fig. 8 is a side view of the tapered cylinder member;

Fig. 9 is an end view thereof;

Fig. 10 is a plan view of one of the grates employed;

Fig. 11 is a plan view of a screen frame;

Fig. 12 is an end view of a grate;

Fig. 13 is an end view of a screen frame;

Fig. 14 is a side view of a drum head connecting bar; and

Fig. 15 is an end view thereof.

Referring now more particularly to the drawing, it will be seen that the numeral 20 indicates the improved cylinder which is in the form of a drum of octagonal shape. The drum heads 21 are of octagonal form with edge portions 22. The inner surfaces of the edge portions 22 are formed with projecting angle portions 23 provided with countersunk bolt holes 23'.

To secure the drum heads together, a plurality of elongated connecting bars 25 are provided, said bars being shaped as shown in Fig. 14 and positioned as shown in Fig. 2. The connecting bars 25 are formed with enlarged ends 26 adapted to be positioned against the head portions 23 and said ends 26 are provided with apertures 27 registerable with the bolt holes 23' to permit the bolting of the connecting bars to the head edge portions.

The drum frame is covered by eight grate members 28 secured thereto by means hereinafter to be explained. The mid-portions of the grates are raised and provided with transverse bars 29 while the flanged edges 30 of the grates are formed to receive frames 31 provided to secure screening 32 to the exposed faces of the grates, it being observed

that the screening is interposed between the grates and the frames 31, and is tightly stretched and clamped in position by means of said frames, as shown in Figs. 1 and 2. To provide for the ready removal of the grates and screening to permit replacement or repairs the drum head portions 22 are provided with slotted openings 33 and the

110

edge portions 30 of the grates 28 and the screen frames 31 have corresponding slots 34 and 35, respectively. The grates and screen frames 31 are positioned on the drum frame members 22 so that the slots 33, 34 and 35 register. Headed bolts 36 are then slipped therein and are clamped in position by means of nuts 37.

Referring more particularly to Figs. 1, 10 6 and 7, it will be seen that the drum head end portions 24 are formed with inwardly projecting ribs 38, and secured to the ribs, longitudinally of the drum, are sheets of metal 39, curved to form buckets, for the 15 purpose hereinafter to be explained.

The drum head portions 24 are further formed with centrally positioned bored hubs 40 to receive shafts 41 which are wedgingly fitted within said hubs, and the inner end 20 portions of said shafts are reduced, as at 41', and the shafts are held against withdrawal from the hubs by nuts 44 threaded onto the reduced end portions 41' and held thereon by pins 45. The shafts 41 project 25 outwardly from the drum heads and are journaled in the sides of the tank in which the drum is positioned, affording means whereby the drum may be rotated.

The inner end portions of the hubs 40 are 30 reduced, as at 42, to removably receive a cylinder member 43, as shown in Fig. 1, said cylinder member being preferably formed in the shape of a double cone, the greatest 35 diameter of which is at approximately the center of the drum. Referring to Fig. 2, it will be seen that the alternate bucket plates 39 are of a size sufficient to reach the surface of the cylinder, and are secured to flanges 46 thereon.

40 When the drum is rotated within the tank in which it is disposed, the pulp within the tank is subjected to jets of water and the

pulp is squeezed between the tank sides and the screens 32. A relatively large proportion of the dirty water will pass through 45 the screens into the interior of the drum. This water is caught by the bucket plates 39 and due to the sloping of the cylinder member 43, it will flow in both directions to the opposite ends of said drum and out 50 through annular passageways 47 provided therefor in the drum head members.

Obviously, the entire cylinder may be readily disassembled to permit repairs and replacement of parts inasmuch as all of 55 the constituent units are bolted together in a manner to permit the quick removal of any unit.

From the foregoing description, it will be seen that the improved cylinder for paper 60 pulp machines is of very simple and novel construction, and is well adapted for the purpose set forth.

What I claim as my invention is:

1. A cylinder for paper pulp machines, 65 comprising a rotatable polygonal frame, a cylinder member of double conical shape removably secured within said frame, spaced bucket members within said frame for directing liquid to the surface of said cylinder member, longitudinally extending grate members removably secured to the frame, and screen members removably secured to the frame and grate members. 70

2. In a cylinder for paper pulp machines 75 having a frame and a cylinder within the frame, bucket members also within the frame, grate members carried by the frame and forming sides, side frames clamped to said grate members; and screening interposed between said grate members and said side frames. 80

In testimony whereof, I affix my signature.

NATHAN H. BERGSTROM.
